UNITED STATES PATENT OFFICE.

WILLIAM W. PHILLIPS, OF CALGARY, ALBERTA, CANADA.

RAILWAY CROSSING AND ALARM SIGNAL.

Application filed January 30, 1923. Serial No. 615,793.

To all whom it may concern:

Be it known that I, WILLIAM W. PHILLIPS, a citizen of the Dominion of Canada, and resident of Calgary, in the county of 5 Calgary and Province of Alberta, Dominion of Canada, have invented certain new and useful Improvements in Railway Crossing and Alarm Signals, of which the following is a specification.

10 This invention has relation to certain new and useful improvements in railway signals and has for its primary object the provision of signals of the character stated especially adapted for use at railway crossings to give 15 audible signals or alarms as the trains and other rolling stock approach the crossing.

Another object of the invention resides in the provision of railway signals of the character set forth which will be extremely 20 simple in construction and operation, inexpensive, composed of the minimum number of parts and accurate and efficient in its operation.

The invention has for a further object the 25 provision of a railway signal of the character stated which may be readily installed at any point desired along the track without alterations in the track construction and which will be arranged in such a manner as 30 to be positively operated by the rolling stock as it passes along the track.

With the foregoing and other objects in view as will appear as the description proceeds, the invention consists in the novel 35 construction, combination and arrangement of co-operating elements as hereinafter more specifically set forth, claimed and shown in the accompanying drawings forming a part of the present application, in which:

40 Fig. 1 is a plan view of a section of a track, showing the railway signal in position.

Fig. 2 is an elevation of the signal showing the track in longitudinal section for the sake 45 of clearness.

Fig. 3 is an enlarged detail section substantially on the plane of line 3—3 of Fig. 2, looking in the direction indicated by the arrows.

50 Fig. 4 is an enlarged detail fragmentary elevation, showing the bell and the striking means therefor forming a part of the invention.

Fig. 5 is an enlarged fragmentary detail

section, showing one of the enclosed guide 55 pulleys for the cable.

Fig. 6 is an enlarged fragmentary detail of the wheel actuated trip positioned at the side of one of the track rails.

Fig. 7 is an enlarged fragmentary section 60 substantially on the plane of line 7—7 of Fig. 2, looking in the direction indicated by the arrows.

Referring more in detail to the drawings in which similar reference characters designate corresponding parts throughout the several views, 10 designates in general a track section including the rails 11 supported in the usual manner on the transverse ties 12. A signal post 13 is mounted outwardly of or to one side of the track, as shown clearly in Fig. 1 and preferably located near a railway crossing to carry the usual crossing sign 14. The audible signal 15, preferably in the form of a gong or bell, is 75 also mounted on the signal post 13 and operated by the striking hammer 16, as shown clearly in Fig. 4. The striking hammer 16 is pivotally mounted on the signal post 13, as shown at 17. The striking hammer 16 is 80 mounted so that the head 18 thereof may readily strike upon the gong or bell and the operating cable 19 is connected with the other end of the striking hammer 16 which extends into the upstanding section 20 of the 85

cable enclosing tubing, a suitable slot 21 being provided in said upstanding section 20 for this purpose, as shown clearly in Fig. 4. The upper end of the upstanding section 20 is closed by a cap 22 or other suitable means. A spring 23 is employed for retaining the striking hammer 16 in normal position, one end of the spring 23 being mounted on the signal post 13 while the other end is pivotally connected with the 90 striking hammer 16 at a point near its pivot connection 17 and the end connecting with the operating cable 19, thereby resiliently retaining the head 18 of the striking hammer 16 adjacent the gong or bell. Suitable 95

supporting straps or brackets 24 are employed to secure the upstanding section 20 to the signal post 13, as shown in Figs. 2 and 4.

One end of the transverse section 25 of the cable enclosing and protecting tubing is connected with the lower end of the upstanding section 20 by means of an L or

corner connection 26 while a similar L or corner connection 27 serves to connect the other end of the transverse section 25 with the longitudinal section 28 of the cable enclosing and protecting tubing. The transverse section 25 is extended beneath the track rail 11 adjacent the upstanding signal post 13 while the longitudinal section 28 is mounted on the transverse ties 12 along the inner side of the other track rail 11. Suitable supporting straps or brackets 29 are employed for holding the longitudinal section 28 in proper position, as shown in Figs. 1 and 2. It may also be stated at this time that the free end of the longitudinal section 28 is open and one end of the operating cable 19 projects out of the same. Attention is also directed, at this time, to the fact that the operating cable 19 passes around suitable guide pulleys 30 which are located in the L or corner connections 26 and 27 and carried on suitable pivot pins 31, as shown in Fig. 5.

The end of the operating cable 19 projecting from the open end of the longitudinal section 28 of the cable enclosing and protecting casing is connected with the upstanding arm 32 of the wheel actuated rock arm 33. This wheel actuated rock arm 33 is mounted on the pivot bolt 34 in the connection of its main portion with the upstanding arm 32 thereof. This pivot bolt 34 is carried on the upstanding branch 35 of the supporting plate 36. This supporting plate 36 is mounted on the transverse ties 12, as shown in Fig. 1, so as to position the upstanding branch 35 thereof against the inner side of the web of one of the rails 11. This permits mounting of the wheel actuated rock arm 33 adjacent the inner side of the rail 11, as shown clearly in the drawings. The upstanding arm 32 is located at one end of the wheel actuated rock arm 33 and an arcuate head 37 is carried on the other upstanding end 38 of the wheel actuated rock arm 33, as shown clearly in Fig. 6. A leaf spring 39 or other suitable member is carried on the under face of the wheel actuated rock arm 33 to resiliently retain the latter in its uppermost position, thereby presenting the arcuate head 37 in the path of travel of wheels of the rolling stock moving over the rail 11 adjacent which the wheel actuated rock arm 33 is mounted. A stop pin 40 is extended laterally from the upstanding branch 35 of the supporting plate 36 to limit upward swinging movement of the wheel actuated rock arm 33, as disclosed in Fig. 6 as well as Figs. 2 and 3. As indicated by dotted lines in Fig. 6, the wheel actuated rock arm 33 will be forced downwardly as a wheel moving on the rail 11 over the arcuate head 37. As soon as the wheel passes the arcuate head 37, however, the leaf spring

39 will act to return the wheel actuated rock arm 33 to normal position. Each operation of the wheel actuated rock arm 33 serves to pull the operating cable 19 and then permit return of the latter to normal position. This results in operation of the striking hammer 16 on the gong or bell to sound the audible signal 15. As the operation of the wheel actuated arm 33 is repeated with the passing of each wheel over the arcuate head 37, a continual operation of the audible signal will be assured as the rolling stock moves along the track past the wheel actuated arm 33.

It is believed the complete construction and operation of the railway signal may now be apparent from the foregoing paragraphs taken in connection with the accompanying drawings without further detailed description. It may be briefly stated, however, that the guide pulleys 30 provide for a free movement of the operating cable 19 and as practically all of the operating cable is enclosed and protected and the other operative parts of the signal are so positioned as to be well protected from snow, ice and the like the complete signal should operate just as effectively in bad or snowy weather as in good weather. In fact, additional covering and protecting members may be employed for the operative parts, as desired.

While the preferred embodiment of the invention has been disclosed, it is to be understood that minor changes in the details of construction, combination and arrangement of co-operating elements may be resorted to within the scope of what is claimed without departing from the spirit of the invention.

What I claim as new is:

1. A railway signal structure including an audible signal; an operating cable for said audible signal; enclosing and protecting means for said operating cable; guiding means within said enclosing and protecting means; a wheel actuated member having a branch connected with said operating cable; said wheel actuated member having a second member with an arcuate head carried thereon and normally in the path of travel of wheels riding on an adjacent track rail; means to resiliently retain said wheel actuated member in normal position; said audible signal including a gong and a striking hammer; said operating cable being connected directly with said striking hammer; and means connected with said striking hammer to resiliently retain the latter in operative position.

2. A railway signal structure including an audible signal; an operating cable for said audible signal; enclosing and protecting means for said operating cable; guiding means within said enclosing and protecting

means; a wheel actuated member having a branch connected with said operating cable; said wheel actuated member having a second member with an arcuate head carried thereon and normally in the path of travel of wheels riding on an adjacent track rail; means to resiliently retain said wheel actuated member in normal position; a supporting plate for said wheel actuated member; means carried by said supporting plate for limiting movement of the wheel actuated member in one direction; said cable enclosing and protecting means being secured along a track section with a portion 10 of said wheel enclosing and protecting means extending longitudinally of the track rail adjacent which the wheel actuated member is positioned; and a signal post located adjacent the track section; a portion 15 of the cable enclosing and protecting means being secured longitudinally of the signal post; said audible signal being mounted on said signal post.

3. A railway signal structure including 25 an audible signal; an operating cable for said audible signal; enclosing and protecting means for said operating cable; guiding means within said enclosing and protecting means; a wheel actuated member having a branch connected with said operating cable; said wheel actuated member having a second member with an arcuate head carried thereon and normally in the path of travel of wheels riding on an adjacent track rail; 30 means to resiliently retain said wheel actuated member in normal position; said audible signal including a gong and a striking hammer; said operating cable being connected directly with said striking hammer; 35 means connected with said striking hammer to resiliently retain the latter in operative position; a supporting plate for said wheel actuated member; means carried by said supporting plate for limiting movement of the wheel actuated member in one direction; 40 said cable enclosing and protecting means being secured along a track section with a portion of said wheel enclosing and protecting means extending longitudinally of 45 the track rail adjacent which the wheel actuated member is positioned; and a signal post located adjacent the track section; a portion 50 of the cable enclosing and protect-

ing means being secured longitudinally of the signal post; said audible signal being 55 mounted on said signal post.

4. A railway signal structure including an audible signal; an operating cable for said audible signal; enclosing and protecting means for said operating cable; guiding means within said enclosing and protecting means; a wheel actuated member having a branch connected with said operating cable; said wheel actuated member having a second member with an arcuate head carried 60 thereon and normally in the path of travel of wheels riding on an adjacent track rail; means to resiliently retain said wheel actuated member in normal position; said cable enclosing and protecting means including 65 sections of tubing extended at different angles and connected by corner members; said cable guiding means being located in said corner members and consisting of rotatably mounted guiding pulleys; and a cap 70 for closing one end of said cable enclosing and protecting means.

5. A railway signal structure including an audible signal; an operating cable for said audible signal; enclosing and protecting means for said operating cable; guiding means within said enclosing and protecting means; a wheel actuated member having a branch connected with said operating cable; said wheel actuated member having a second branch with an arcuate head carried 80 thereon and normally in the path of travel of wheels riding on an adjacent track rail; means to resiliently retain said wheel actuated member in normal position; said audible signal including a gong and a striking hammer; said operating cable being connected directly with said striking hammer; 85 means connected with said striking hammer to resiliently retain the latter in operative 90 position; said cable enclosing and protecting means including sections of tubing extended at different angles and connected by corner members; said cable guiding means being located in said corner members and 95 consisting of rotatably mounted guide pulleys; and a cap for closing one end of said cable enclosing and protecting means.

In testimony whereof, I affix my signature.

WILLIAM W. PHILLIPS.
